[57] CLAIM

The ornamental design for a handle for pocket blade, as shown and described.

DESCRIPTION

FIG. 1 is a perspective view of the handle for pocket blade showing our new design.

FIG. 2 is a top plan view thereof, the bottom view being identical.

FIG. 3 is a side elevational view thereof, the opposite side being a mirror image.

FIG. 4 is an end elevational view thereof, the opposite end being identical.

The broken line showing of the blade, chain and button in FIG. 1 is for illustrative purposes only and forms no part of the claimed design.
